UNITED STATES PATENT OFFICE.

CHARLES B. KENT, OF KENOSHA, WISCONSIN.

CARBURETER.

1,141,086.

Specification of Letters Patent. Patented May 25, 1915.

Application filed August 7, 1914. Serial No. 855,714.

To all whom it may concern:

Be it known that I, CHARLES B. KENT, a citizen of the United States, and a resident of Kenosha, in the county of Kenosha and 5 State of Wisconsin, have invented certain new and useful Improvements in Carbureters, of which the following is a specification.

My invention relates to carbureters and 10 particularly to that class in which a piston air valve and a fuel nozzle coöperate to control the quantity and quality of the mixture to be delivered from the carbureter.

Among the important objects of the invention are to provide improved air inlet and directing mechanism for causing more efficient fuel feed and more efficient mixture of the fuel with the air before delivery from the carbureter; to provide improved means 20 for preventing fluttering and pounding of the piston air valve particularly when the engine fed by the carbureter is running at low speed; to provide means for enabling adjustment of the carbureter in order that 25 it may be more readily installed in different styles of cars; to provide improved and simple structure of the piston air valve; to provide improved and more efficient mechanism for readily adjusting the fuel inlet; 30 and in general to provide simple, inexpensive yet efficient carbureter which is devoid of intricate and delicate parts and adjustments and which is exceedingly light and adapted to be readily and quickly installed 35 in different styles of cars.

The above and other features of the invention are shown on the accompanying drawings in which—

Figure 1 is a side elevational view of the 40 carbureter, a part of the inclosing shell being broken away; Fig. 2 is a plan view; Fig. 3 is a sectional view on plane 3—3, Fig. 2; Fig. 4 is a sectional view like Fig. 3 but showing a different adjustment of the fuel valve; Fig. 5 is a sectional view on plane 45 5—5, Fig. 3; and Fig. 6 is a side elevational view of the piston valve.

The carbureter proper comprises a cylindrical cup-shaped body 10 which has the 50 top flange 11 adapted for connection with the inlet pipe or manifold of an engine. The upper part of the body forms a mixing chamber 12 from which the outlet is controlled by the butterfly valve 13 mounted on 55 a shaft 14 from which the actuating lever 15 extends. The shaft also carries a hub 16

from which extend abutment arms 17 and 18 for coöperating with the abutment 19 to limit the opening and closure movement of the valve.

Adapted to reciprocate in the body part is 60 a cup-shaped piston valve 20. This valve has in its base the opening 21 and in its cylindrical wall has the zone of air inlet ports 22, 22 adapted to register with inlet 65 passageways 23, 23 in the body 10.

The base of the body 10 has the opening 24 through which passes the lower end of a Venturi tube structure 25. The upper end of this tube structure is externally cylindrical and passes through the opening 21 in the base of the piston air valve, a collar or flange 26 on the tube forming a seat for the piston or valve when in its lowermost position. The base of the tube structure 25 has 70 the opening 27 through which extends the stem 28 whose upper end is tapered to form the nozzle 29. The opening 27 is threaded and the stem 28 is also threaded in order that vertical adjustment of the nozzle with- 75 in the Venturi tube may be readily accomplished. Below the base of the body 10 the tube 26 has radial air inlet passageways 30, the Venturi passageway through the tube contracting gradually toward the nozzle outlet and then flaring at its upper end. Preferably the nozzle outlet is normally at the narrowest part of the tube in order that air entering through passageways 30 will during its passage through the tube have ob- 80 tained its greatest velocity and concentration adjacent the nozzle outlet, the suction effect on the nozzle being then the most efficient. The air and the fuel withdrawn there- 85 by from the nozzle will immediately mix and will be thrown radially outwardly from the end of the Venturi tube toward the zone of air passageways 23 in the body 10 in order that when these passageways are opened as the piston valve is raised the additional in- 90 coming air will meet the mixture coming from the Venturi tube and an efficient final mixture will take place before delivery from the carbureter.

The flow of fuel from the nozzle is con- 95 trolled by the needle valve 31 secured to the diametral cross bar 32 of the piston valve and depends therefrom into the nozzle. When the air valve and nozzle are separated 100 more fuel will flow and when they are brought together less will flow, the fuel being fed in any suitable manner to the 105

nozzle through the stem bore 33 and radial passageways 34 thereto. The nozzle stem 28 having threaded engagement in the base of the Venturi tube and the flange 26 on the tube limiting the downward movement of the piston valve, the nozzle can be readily adjusted with reference to the needle valve. As best shown in Fig. 3, the piston valve normally rests on the collar of the Venturi tube with its ports 22 just below the inlet nozzle but does not quite close it, the nozzle outlet being always above the level of fuel in a reservoir which will be described later. When an engine is started the suction will directly cause fuel to be drawn upwardly through the nozzle and will cause air to be drawn into the Venturi tube through passageways 30, this up-flowing air concentrating and acquiring velocity through the restricted Venturi tube and producing suction effect at the nozzle outlet to assist the direct suction thereon in drawing fuel from the nozzle. The mixture of air and fuel is deflected radially outwardly by the flaring end of the Venturi tube and will meet additional air coming in through ports 22 as the valve is raised by the engine suction to bring these ports into register with the body passageways 23, final mixture taking place in the upper part of the body 10 before delivery to the engine. A stop block 35 is preferably provided in the body 10 to limit the upward movement of the piston valve.

In prior structures involving a cylindrical body it is necessary to provide guide means for the valve in order to keep the ports of the valve in vertical alinement with the air passageways and to prevent the partitions between the ports from overlying the air passageways. One of the important objects of my invention is to eliminate the installing of such special guide means. As clearly shown in the figures the bands 22' remaining in the air valve after the ports 22 are cut therein are bowed or bent inwardly. With this arrangement it is unnecessary to provide guide means for preventing rotation of the valve as even though the curved bands should overlie the passageways 23 in body 10 they will not interfere with nor reduce the flow of air.

Another object of the invention is to prevent fluttering or pounding of the air valve while the engine is working. Where the air valve is free to reciprocate it will follow the movements of the engine piston particularly at the lower speeds and the valve will suddenly drop as soon as the suction effect is reduced and will strike its stop. To prevent such fluttering of the air valve I provide check valves 36, each valve comprising a cup *a* extending through the base of the body 10 and opening into the body, the cup being provided with a valve outlet *b* normally closed by a ball *c*, a bar *d* preventing

escape of the ball. As the base of the air valve closely encircles the Venturi tube 25, the bottom of the body 10 together with the tube and the base of the valve forms a dash pot together with the check valves, this dash pot preventing sudden downward movement of the air valve as the suction decreases and to prevent fluttering of the valve during running of the engine. The air valve can, however, quickly respond to the suction and during running of the engine will be practically maintained in its upper position and prevented from suddenly dropping at the end of each engine stroke.

The structure thus far described can be used alone together with some other oil feed to the stem 28. However, I prefer to provide a housing or supporting frame for the carburetor parts. As shown, such housing comprises a central cylindrical part 37 concentric with the body 10 but of larger diameter and of a height to surround the air passageways 23. A lateral cylindrical extension 38 from the part 37 has pivoted therein a butterfly valve 39 for controlling the air flow to the carburetor parts, the valve being pivoted on a stem 39' which extends to the exterior and has secured thereto a hub 40 from which extend operating levers 41 and 42, the throw of the levers being controlled by stops 43 and 44 co-operating with an abutment post 45. The extension 38 may take in air directly from atmosphere or it may connect with a pipe leading from some device in which the air is heated by the engine exhaust or otherwise. Where the frame is thus connected with an air heating source a direct air inlet 46 may be provided in the part 38 and controlled by a shutter 47. In the base of the frame part 37 is a threaded pocket 48 in which the threaded lower end of the Venturi tube structure 25 seats. The collar 26 on this Venturi tube structure engages against the inside of the base of the body 10, and extending downwardly from said base are pins 49 for spacing the body sufficiently away from the bottom of the part 37 to permit free passage of air through the check valves 36. When the Venturi tube is screwed into the pocket 48 the collar 26 will draw the pins against the bottom of the part 37 and will thus lock the body 10 in place. Extending downwardly from the body part 37 below the pocket 48 is the neck or sleeve 50 through which the nozzle stem 28 extends, the lower part of this stem being provided with the knurled head 51 whereby it may be readily turned to effect adjustment of the nozzle with reference to the needle valve.

Extending laterally from the central part 37 on the side opposite to that from which the part 38 extends is the fuel reservoir 52, a duct 53 extending from this reservoir to

the neck 50. Within this neck is a sleeve 54 whose external diameter is less than the internal diameter of the neck and whose internal diameter is greater than the diameter of the stem in order to provide external and internal annular compartments 55 and 56 respectively. The lower end of the sleeve is of enlarged diameter to fit the neck and stem and is beveled in order to coöperate with the beveled collar 57 to form a space for receiving packing material p . The collar 57 extends from the hollow nut 58 which has threaded engagement with the exterior of neck 50. The upper section 50' of the neck 50 is of reduced internal diameter to fit the stem 28, and its lower surface is beveled to coöperate with the upper beveled surface of a ring 59 to form a space for packing material p' , the sleeve 54 abutting at its upper end against the ring 59. With this arrangement when the nut 58 is drawn up the annular compartments 55 and 56 are inclosed and leakage therefrom prevented. The fuel duct 53 leads to the outer chamber 55 and the fuel can flow to the inner chamber through passageways 60, the radial passageways 34 to the bore of stem 28 communicating with the inner chamber. The arrangement is such that the outlet of the nozzle is at all times sufficiently above the level of the fuel in the reservoir to prevent the flow of fuel from the nozzle except when the engine is running. In the reservoir shown I have provided a float 61 which rests on the outer arms of bell crank levers 62, 63 pivoted between ears 64 and 65 on the inner face of a plug 66 and at the opposite sides of the central bore 67 through the plug. The inner ends 68, 69 of the levers are forked for receiving between them the valve pin 70 which coöperates with the seat 71 provided in the block 66. The pin extends from a stem 72 which rests on the forked ends 68, 69 and tends to counter balance the float. The reservoir is provided with a cover 73 which has the central sleeve 74 through which the upper end of the stem 72 extends, a cap 75 being provided for this sleeve. Extending from the lower end of the plug 66 is a fitting 76 adapted for connection with a fuel supply pipe.

preferably provided for the reservoir. As shown, such vent is provided in the cover 75. The fuel flows from the reservoir through duct 53 and chambers 55 and 56 into the stem 28 and thence upwardly into the nozzle whose outlet end is always slightly above the level of the fuel in the reservoir. When the engine is started air will enter through extension 38 and will flow first into the Venturi tube through the passageways 30 and will then flow upwardly through the contracted Venturi tube to effect suction on the nozzle which together with the direct suction on the nozzle will cause fuel to be drawn out of the nozzle and this fuel is immediately picked up by the air and mixed therewith. The mixture is thrown radially outwardly by the flaring end of the Venturi tube to mix with the air flowing through passageways 23 and 24 as soon as the air valve is raised high enough to bring these passageways into registration. Owing to the provision of a dash pot below the piston valve fluttering of the valve is prevented particularly during the starting period of the engine.

If a richer mixture is desired the stem 28 is turned to effect downward movement of the nozzle to bring the nozzle outlet to a smaller diameter of the needle valve, while if a less rich mixture is desired the stem 28 is turned to effect upward shift of the nozzle to bring its outlet to a larger diameter of the needle valve. 95

The parts 37 and 38 and 52 of the housing 100 are preferably in the form of an integral casting and may be of aluminum. With such light housing and with the simple carburizing parts the structure is very light and small. 105

As there are so many different styles of vehicles and engines it is very difficult to fit one style of carbureter to all the various conditions unless some adjustment is provided for. In my improved carbureter I 110 adapt the body part 10 with its flange 11 for rotary movement in the frame part 37 and also provide for rigidly securing the body part to the frame after any adjustment thereof. As clearly shown, a flange 115 78 extends upwardly from the part 37 and around the body 10 and has the vertical slots 79. Surrounding this flange is a clamping ring 80 whose lugs 81 and 82 are connected by a screw 83. When the screw is 120 loosened the body 10 can be freely rotated to bring the coupling flange 11 in any angular position and upon tightening of the screw the ring will be contracted and the sections of the flange 78 between the slots 79 will be drawn against the body 10 to hold 125 it in place. This adjustment can readily be made to enable better and more ready installation of the carbureter under different conditions. To provide for more efficient 130

operation of the engine when it is "idling" and to prevent stopping thereof under such slow running conditions, I provide a small hole 84 through the throttle valve 13, this opening being centrally through the valve or as close to the center as possible. When the engine is "idling" the butterfly valve is practically wholly closed, and I have found that without such hole 84 the air which is drawn into and slowly through the Venturi tube will tend to hug the wall thereof and flow more or less radially to escape around the edges of the practically closed throttle valve, and that at times therefore there is not sufficient suction effect on the nozzle to draw enough fuel to keep the engine going and the engine stops suddenly. However, by providing a hole 84 the air will tend to flow more toward the axis of the Venturi tube along the outside of the nozzle in order to escape through the hole in the throttle valve and there is greater suction effect on the nozzle and sufficient fuel is at all times drawn out with the air to keep the engine running idle at very slow speed.

I claim—

1. In a carbureter, the combination of a cylindrical body part, an air duct extending upwardly into said body part, said duct opening to atmosphere at its lower end and opening into the body part at its upper end, a piston valve reciprocable in said body part and having air ports, said body part having air passageways, said valve ports being entirely below said body part air passageways when the valve is in its lowermost position, a nozzle extending upwardly through said air duct, a needle valve suspended from the air valve and extending into said nozzle, said nozzle being longitudinally adjustable in said air duct, and means for delivering fuel to said nozzle.
2. In a carbureter, the combination of a cylindrical body part having air passageways, an air duct extending upwardly into the body part through the base thereof and open at its outer end to air, a cup-shaped piston air valve having an opening at its base for receiving said duct, said duct having a stop for limiting the downward movement of said air valve and said air valve having air ports which are entirely below the body part air passageways when the air valve rests on said stop, a fuel nozzle extending longitudinally into said air duct, a needle valve carried by said air valve and extending into said nozzle, said nozzle being adjustable in said air duct, and means for delivering fuel to the nozzle.
3. In a carbureter, the combination of a cylindrical body part, a Venturi air tube extending into said body part, a nozzle projecting into said Venturi tube and adjustable therein from the exterior, a cup-shaped piston air valve reciprocable in said body

part, ports in said air valve and air passageways in said body part, and a fuel valve extending from said piston air valve and co-operating with said nozzle to control the flow of fuel therefrom.

4. In a carbureter, the combination of a cylindrical cup-shaped body part having an opening through its base, a Venturi air tube seated in said opening and extending into the body part and having its outer part open to atmosphere, an exterior flange on said tube within the body part, a cup-shaped piston air valve having an opening in its base for receiving the tube, said flange limiting the downward movement of said piston valve, said piston valve having air ports and said body part having air passageways, a fuel nozzle extending into said Venturi tube and adapted for connection with a source of fuel, and a needle valve carried by said piston valve and extending into said nozzle to control the flow of fuel therefrom.

5. In a carbureter, the combination of a cylindrical body part, carbureting mechanism associated therewith, a coupling flange at the outer end of said body part, an inclosing frame having a passageway into which said body part detachably extends, and a clamping ring engaging said inclosing frame to clamp said frame to the body part after adjustment of said body part to bring the coupling flange into desired position.

6. In a carbureter, the combination of a cup-shaped body part having an opening in its base, a Venturi tube frame extending into said body part through said opening and open to atmosphere below said body part, said tube having a shoulder and the section above said shoulder being of cylindrical outer surface, a cup-shaped piston valve having an opening in its base for receiving said cylindrical section of the Venturi tube and the shoulder on said tube forming an abutment for said valve to limit the downward movement thereof, a nozzle extending into said tube, a needle valve extending from said piston into said nozzle, said piston valve responding to suction created in said body part when an engine is connected therewith, the space between the lower walls of said body part and the base of said piston valve and the sides of said Venturi tube forming a dash pot compartment for the piston valve, and check valves communicating with said compartment for allowing ready response of the piston valve to suction but for retarding its return movement.

7. In a carbureter, the combination of a supporting frame, a Venturi tube secured to and extending upwardly from said frame and having air inlet at its lower end, a body part extending into said frame and having an opening in its base for receiving said tube, said tube having a shoulder for re-

taining said body part in said frame, a nozzle extending into said Venturi tube, a piston valve reciprocable within said body part, and a needle valve carried by said piston valve and extending into said nozzle.

8. In a carbureter, the combination of a supporting frame, a cup-shaped body part extending into said frame and having an opening in its base, a Venturi tube having its lower end extending through said opening and secured in said frame and having a shoulder for engaging the base of the body part to retain the body part in the frame, a nozzle extended into said Venturi tube, a piston valve reciprocable within said body part, and a needle valve extending from said piston valve into said nozzle.

9. In a carbureter, the combination of a supporting and inclosing frame, a cup-shaped body part extending into said frame and having spacing extensions on its base for engaging said frame, the base of said body part having an opening, a Venturi tube having its lower end extended through said opening and secured to the body part, a shoulder on said tube for engaging the base of the body part to retain it in said frame, said tube having air inlets communicating with the space between the base of the body part and said frame, a nozzle extending into said Venturi tube from the exterior of said frame, a piston valve reciprocable in said body part, and a needle valve carried by said piston valve and extending into said nozzle.

35 10. In a carbureter, the combination of an inclosing frame, a Venturi tube secured at its base to said frame and extending upwardly therein, a cup-shaped body part extended into said frame and having an opening in its base for receiving said tube, a cup-shaped piston valve within the body part having an opening in its base for receiving said tube, a nozzle extended into said tube from the exterior of said frame, and a needle valve carried by the piston valve and extending into said nozzle.

11. In a carbureter, the combination of an

inclosing frame, a Venturi tube secured at its base to said frame and extending upwardly therein, a cup-shaped body part extended into said frame and having an opening in its base for receiving said tube, a cup-shaped piston valve within the body part having an opening in its base for receiving said tube, a nozzle extended through said frame from the exterior thereof and into said Venturi tube, said nozzle having threaded engagement with the base of said tube and having a head at its outer end whereby it may be readily turned to be adjusted with reference to said tube, and a needle valve carried by said piston and extending into said nozzle.

12. In a carbureter, the combination of an inclosing frame having a neck, a body part extending into said frame through said neck, carbureting mechanism within said body part, and a clamping strap encircling said neck to clamp said body part securely to said frame.

70 13. In a carbureter, the combination of an inclosing frame having a slotted neck, a body part extending into said frame through said neck, carbureting mechanism within said body part, and a clamping strap encircling said slotted neck for clamping said neck securely against the body part to lock the body part to said frame.

14. In a carbureter, the combination of a body part, a Venturi tube extending into said body part, a nozzle extending upwardly into said Venturi tube through the base thereof and having threaded engagement with said base whereby it may be longitudinally adjusted with reference to said tube, a piston valve within the body part, and a needle valve extending from said piston valve into said nozzle.

In witness whereof I hereunto subscribe my name this 3rd day of August, A. D. 1914.

CHARLES B. KENT.
